(57) **CLAIM**

The ornamental design for a collar attachment, as shown and described.

DESCRIPTION

FIG. 1 is a front perspective view of a collar attachment;

FIG. 2 is a front view thereof;

FIG. 3 is a back view thereof;

FIG. 4 is a right side view thereof;

FIG. 5 is a left side view thereof;

FIG. 6 is a top side view thereof;

FIG. 7 is a bottom side view thereof; and,

FIG. 8 is a back perspective view thereof.

Note that any broken line illustration of environmental structure in the drawing is not part of the design sought to be patented.
